LADY'S STOCKING

Clyde A. Berry, Valdese, N.C., assignor to Pilot Research Corporation, Valdese, N.C., a corporation of North Carolina

Filed Apr. 18, 1966, Ser. No. 1,930

Term of patent 14 years

(Cl. D2—336)

The figure is a side elevation of a lady's stocking showing my new design. The opposite side is a mirror image of the side shown.

The characteristic feature of my design resides in the combination in the lady's stocking disclosed of the straight line front edge extending substantially from the toe pocket to the welt or top portion with the matching straight line rear edge defining foot and ankle portions together with the shaped calf and thigh portions, substantially as shown.

I claim:

The ornamental design for a lady's stocking, substantially as shown and described.
